UNITED STATES PATENT OFFICE.

JOSEPH I. SMITH, OF OGDEN, UTAH.

FOLDING BED.

Application filed October 12, 1923. Serial No. 668,144.

To all whom it may concern:

Be it known that I, JOSEPH I. SMITH, a citizen of the United States, residing at Ogden, in the county of Weber and State of Utah, have invented certain new and useful Improvements in Folding Beds, of which the following is a specification.

My invention relates to a folding bed, to be mounted upon the running board of an 10 automobile, or like vehicle.

An important object of the invention is to provide a bed of the above mentioned character, the parts of which may be collapsed into a very compact form, for arrangement within a casing or trunk, to be attached to the running board, whereby the appearance of the device when folded, will be neat and attractive.

A further object of the invention is to 20 provide a folding bed of the above mentioned character, which is extremely strong, light and durable.

A further object of the invention is to provide a combination folding bed and casing or trunk, with the outer side of the casing serving as a table for use in connection with the bed.

Other objects and advantages of the invention will be apparent during the course 30 of the following description.

In the accompanying drawings, forming a part of this specification, and in which numerals are employed to designate like parts throughout the same,

35 Figure 1 is a perspective view of the bed and casing, showing the bed folded, and the outer side of the casing removed,

Figure 2 is a perspective view of the outer side of the casing, also serving as a table top.

40 Figure 3 is a perspective view of the apparatus, the bed spring being omitted for the sake of clearness, showing the bed partly collapsed,

45 Figure 4 is a similar view showing the bed completely opened,

Figure 5 is a central vertical longitudinal section through the bed, opened,

50 Figure 6 is an enlarged side elevation of the inner ends of the longitudinal rail sections of the bed, and associated elements,

Figure 7 is a plan view of the same, and,

55 Figure 8 is a perspective view of the outer side of the casing, viewed from the under side of the same.

In the drawings, wherein for the purpose of illustration is shown a preferred embodiment of my invention, the numeral 10 designates a casing, preferably simulating a trunk. This casing embodies a bottom 11, 60 vertical ends 12, an inner side 13, and a top section 14, as shown. The casing is rigidly mounted upon the running board 15 of an automobile, by any suitable means.

The numeral 16 designates a movable top section or cover, embodying a top section 17, side section 18, and ends 19, as shown. The top section 17 is hinged to the top section 14, to swing in a vertical plane, as indicated at 20. The ends 12 have openings 70 or cut-away portions 21, for the reception of ends 19.

The outer side of the casing 10 is formed open and is adapted to be covered by a side or combined side and table top 22, preferably simulating the side of a trunk. This side 22 is provided upon its inner face with a rectangular marginal flange 23, adapted to engage within the bottom and ends of the casing 10, to prevent end play of the side 22 80 therein. The lower edge of the side 22, projecting beyond the flange 23, engages within brackets or catches 24, which prevents this lower end from partaking of outward movement. The upper end of the side 22 is 85 equipped with a trunk latch element 25, for detachable connection with coacting trunk latch elements 26, carried upon the swinging top or cover 16. The side 22 is also provided with a trunk lock element 27, for engagement with a coacting trunk lock element 28, which is secured to the swinging top or cover 16, as shown. It is thus seen that when the side 22 is in the closed position, upon the casing 10, and the top or 90 cover 16 is swung downwardly, that the side 22 may be locked in the closed position.

The side 22 is also adapted to function as a table top, in a manner to be described, and for this purpose I hinge foldable legs 100 29 upon the inner face thereof, Figure 8, which legs are adapted to fold within each other, to be arranged substantially flat, in contact with the inner face of the side 22, within the flange 23. These legs are adapted to be swung outwardly to depend from the element 22, at a right angle thereto, and may be locked in the outer position by means of a hook 30, for engagement within an eye 31.

The folding bed embodies foldable longitudinal rail sections 32 and 33, which are preferably angle irons of inverted L-shape in cross section. Each rail section embodies 5 a vertical web 34 and a horizontal web 35.

As more clearly shown in Figure 6, the numeral 37 designates a pivot plate, arranged upon the outer side of the vertical webs 34, in contact therewith. This plate 10 is pivotally connected with webs 34 by pivot elements 38', which may be in the form of rivets or any other suitable means. The pivot plate 37 projects downwardly beyond the webs 34 for a substantial distance. The 15 two pivot plates 37 are connected by a transverse bridge rod 38, the ends of which are preferably shouldered and screw threaded for receiving clamping nuts 39. The lower edges of the vertical webs 34, which are 20 arranged in the same plane, have notches 39 therein, for receiving the bridge rod 38, when the bed is folded.

The numeral 40 designates diagonal braces or links, disposed at each side of 25 the bed bottom, and arranged inwardly of and adjacent to the lower end of each pivot plate 37. These links are pivoted at their lower ends, as shown at 41, while the upper ends of these links are disposed upon 30 the inner side of the webs 34 and are pivoted thereto at 42. The pivot plate 37 being arranged upon the outer side of the webs 34, and the links 40 upon the inner side thereof, positions these parts in different planes. 35 When the rail sections 32 and 33 are shifted to the open horizontal position, Figure 4, the bridge rod 38 engages the lower ends of the diagonal braces or links 40, and hence a powerful lock or brace is provided, for 40 holding the rail sections 32 and 33 against downward movement.

Arranged upon the inner sides of each pair of vertical webs 34, see particularly 45 Figures 5, 6 and 7, is a lock plate 43, pivoted to the webs 34 by the pivot elements 38'. This lock plate is arranged beneath the horizontal webs 35 and carries an upwardly projecting tongue or bolt 43', to engage within notches 44, which notches are brought 50 into registration, when the rail sections 32 and 33 are shifted to the horizontal position. The lock plates with their tongues or bolts 43', and associated elements, serve to securely connect or lock the inner ends 55 of the rail sections 32 and 33 together, when shifted to the horizontal position, Figure 4, and particularly lock them against horizontal or lateral relative movement. The pivot plate 37 and the lock plate 43 function 60 to provide a powerful connection between the rail sections 32 and 33.

The outer end of the foldable bed is adapted 65 to be supported in the horizontal or open position by means of a foot element 45, embodying legs 46, connected by horizontal

transverse bars 47. Each leg 46 is pivotally connected at 48 with an upper horizontal strap or link 49, projecting upon the inner side of the web 34 of the rail section 33, and pivoted thereto at 50. The numeral 51 designates a lower diagonal strap or link, the lower end of which is pivoted to the leg 46, at 52, while its upper end is pivoted to the web 34, at 53, the pivot points 50 and 53 being spaced, as shown. The 75 strap or link 51 is preferably offset laterally outwardly, as shown, whereby the strap 49 may fold inwardly of the same. The arrangement is such that the foot element is adapted to be folded flat within the rail sections 33, as indicated in Figure 3.

The rail sections 33 are rigidly connected by means of a transverse rail 54, arranged above the same at their outer ends. The rail sections 32 are rigidly connected at their 85 inner ends by a transverse rail 55, disposed above the same, at their inner ends, as shown.

The inner ends of the side rail sections 32 are pivoted to swing in a vertical plane to 90 angle irons 56, as indicated at 57. These angle irons are securely anchored upon the bottom 11 of the casing 10, adjacent to the ends 12. The rail sections 32 and 33 fold upwardly within the casing 10, and assume 95 substantially vertical positions, and the then lower ends of the rail sections 33 are locked to the horizontal angle irons 56 by means of sliding bolts 58, attached to the transverse rail 54, and adapted to engage within openings 59, formed in the rails 56.

The bed may be equipped with any suitable form of flexible spring or bottom, and I have shown a spring bottom 60, Figure 1, the ends of which are attached to the transverse rails 54 and 55. This spring bottom embodies side straps 61, which may be formed of metal, and having their inner ends connected by flexible inserts 62, which may be formed of leather. These inserts 110 are adapted to fold over a transverse band or strap 63, having connection at their ends with springs 64, which are in turn attached to the inner ends of the horizontal webs 35, as shown at 65.

The operation of the bed is as follows:

When the rail sections 32 and 33 are folded to the vertical position, Figure 1, their inner edges substantially contact, and the pivot plates 37 are vertical, with the bridge 120 rod 38 entering the notches 39. To arrange the bed horizontally for use, Figure 4, the top or cover section 16 is swung to the open position, Figure 1, and the side 22 removed. The rail sections may now be shifted to the 125 horizontal position, as indicated in Figures 3 and 4, and the foot element 45 is arranged vertically, with the upper strap or link 49 engaging beneath the horizontal web of the rail section 33. The bridge rod 38 will en- 130

gage with the lower ends of the diagonal braces or links 40, and a double triangular structure is produced, positively locking the inner ends of the rail sections against downward movement beyond the horizontal. The locking plates 43 also aid in this action, and further prevent lateral relative movements of the rail sections. When folded horizontally, Figure 4, the flexible bottom or spring 10 60 is properly tensioned.

An important feature of the invention is the provision of the side element 22, which when the legs 29 carried thereby are swung outwardly, is adapted to function as a table, 15 for use in connection with the bed. The table may be arranged near the bed and the user may sit upon the bed and eat from the table.

It is to be understood that the form of 20 my invention herewith shown and described is to be taken as a preferred example of the same, and that various changes in the shape, size, and arrangement of parts, may be resorted to, without departing from the spirit 25 of my invention, or the scope of the subjoined claims.

Having thus described my invention, what I claim is:

1. A folding bed for an automobile or the 30 like, comprising a frame embodying foldable side rails, pivot plates pivotally connected with the inner ends of the side rails and projecting downwardly below the same when the side rails are in the substantially horizontal 35 position, a transverse bridge rod connecting the lower ends of the pivot plates, pairs of diagonal links rigid in their vertical planes pivoted at their upper ends to the side rails at points spaced outwardly from 40 the pivot points of the pivot plates, means pivotally connecting the lower ends of the diagonal links in each pair, such lower ends being adapted for contact with the bottom of the transverse bridge rod, the pairs of 45 links being free from connection with the pivot plates and bridge rod and adapted to be positively moved out of contact with the bridge rod when the side rails are folded, means for pivotally connecting one end of 50 the frame with the automobile, and means for supporting the outer end of the frame when in the open position, and a foldable bed bottom carried by the frame.

2. A folding bed for automobiles or the 55 like, comprising a frame embodying foldable side rails, pivot plates arranged upon the outer sides of the rails near their inner ends and pivotally connected therewith, said pivot plates extending downwardly beyond the 60 rails when the rails are in the substantially horizontal position, a transverse bridge rod connecting the pivot plates, pairs of diagonal links rigid in their vertical planes arranged upon the inner side of the side rails and pivotally connected therewith at points spaced

outwardly from the pivots of the pivot plates, means pivotally connecting the lower ends of the diagonal links in each pair, such lower ends being disposed inwardly of the pivot plates and arranged to engage with the lower side of the transverse bridge rod, said pairs of links being free from connection with the pivot plates and bridge rod and adapted to be positively moved out of contact with the bridge rod when the side 75 rails are folded, means for pivotally mounting the inner end of the frame upon the automobile, a collapsible leg element carried by the outer end of the frame, and a foldable bed bottom carried by the frame. 80

3. A folding bed for automobiles or the like, comprising a frame embodying foldable side rails, said rails having vertical and horizontal webs, said horizontal webs being provided at their inner ends with openings, 85 a pivot plate arranged upon one side of the vertical webs and pivotally connected therewith near their inner ends and projecting downwardly below such webs when the side rails are in the substantially horizontal 90 position, a transverse bridge rod connecting the pivot plates, diagonal links pivoted to the side rails and having their inner ends pivotally connected, such inner ends being arranged to engage beneath the bridge rod 95 when the side rails are shifted to the open position, lock plates arranged upon the opposite side of the vertical webs and pivoted to the same near their inner ends and carrying upwardly projecting tongues to enter the openings in the horizontal webs, means for pivotally connecting the inner ends of the frame with the automobile, and foldable means carried by the outer end of the frame 100 to support the same, and a bed bottom carried by the frame. 105

4. A folding bed for automobiles or the like, comprising a frame embodying foldable side rails, pivot plates arranged upon the outer sides of the rails near their inner 110 ends and pivotally connected therewith, a transverse bridge rod connecting the pivot plate, diagonal links pivoted to the side rails and pivotally connected at their lower ends, said lower ends engaging beneath the bridge 115 rod, lock plates arranged upon the inner side of the side rails and pivotally connected therewith near their inner ends, said lock plates having means for interlocking engagement with the inner ends of said rails, 120 means pivotally connecting the inner end of the frame with the automobile, a foldable support for the outer end of the frame, a supporting element extending transversely of the frame near its center and connected 125 with the inner ends of the side rails, and a bed bottom attached to the frame and foldable transversely about the supporting element.

5. In a folding bed, a foldable frame in- 130

cluding side rails, pivot plates pivotally connected with the ends of the side rails, a bridge rod connecting the pivot plates and disposed beneath the side rails, pairs of diagonal links rigid in their vertical planes pivoted to the side rails at points spaced from the pivots of the pivot plates, means pivotally connecting the inner ends of the links in each pair, such inner ends being arranged to contact with the bottom of the bridge rod, said pairs of links being free from connection with the pivot plates and the bridge rod and adapted to be positively moved out of contact with the bridge rod when the side rails are folded, a bed bottom

carried by the frame, and means for supporting the ends of the frame.

6. In a folding bed, a foldable frame including side rails having horizontal and vertical webs, the horizontal webs having notches at their inner ends, locking plates pivotally connected with the vertical webs near their inner ends and carrying upwardly projecting tongues to enter said notches in the horizontal webs, a bed bottom carried by the frame, and means for supporting the ends of the frame.

In testimony whereof I affix my signature.

JOSEPH I. SMITH.
